UNITED STATES PATENT OFFICE

161,721

BASE FOR A HOSIERY LEG FORM

Charles Vermann, New York, N. Y.

Application November 8, 1949, Serial No. 5,927

Term of patent 3½ years

(Cl. D80—9)

To all whom it may concern:

Be it known that I, Charles Vermann, a citizen of the United States of America, residing in New York city, county of New York, and State of New York, have invented a new, original, and ornamental Design for a Base for a Hosiery Leg Form, of which the following is a specification, reference being had to the accompanying drawing, forming part thereof, wherein,

Figure 1 is a front perspective view of a base for a hosiery leg form, showing my new design.

Figure 2 is a side elevational view of the base for a hosiery leg form, and

Figure 3 is a rear elevational view of the base for a hosiery leg form shown in Figures 1 and 2.

I claim:

The ornamental design for a base for a hosiery leg form, substantially as shown.

CHARLES VERMANN.
